UNITED STATES PATENT OFFICE.

HANS M. BOE, OF MINNEAPOLIS, MINNESOTA.

GREASE-GUN.

1,339,916.

Specification of Letters Patent. Patented May 11, 1920.

Application filed March 27, 1915. Serial No. 17,518.

To all whom it may concern:

Be it known that I, HANS M. BOE, a citizen of the United States, and a resident of Minneapolis, in the county of Hennepin and 5 State of Minnesota, have invented a new and useful Improvement in Grease-Guns, of which the following is a specification.

My invention relates to a container for grease in a paste or semi-fluid form, having a pipe and flexible hose by means of 10 which the grease may be accurately and quickly applied by air under pressure to the point of use.

A further object is to provide a container 15 which will accurately measure the amount of grease dispensed and a container which can be easily and quickly recharged.

A further object is to provide a container of light and simple construction that is conveniently portable and may be used for 20 greasing differentials and transmissions of automobiles and for other purposes.

The invention consists generally in various constructions and combinations, all as 25 hereinafter described and particularly pointed out in the claims.

In the accompanying drawings forming part of this specification,

Figure 1 is a vertical section of a device 30 embodying my invention.

Fig. 2 is a top view of the cover and locking levers,

Fig. 3 is a top view of the indicating dial, showing the rewinding spring and supporting member for the indicating dial,

Fig. 4 is a top view of the piston.

The container is preferably cylindrical in form, and for the most part is of well known construction. The air is forced in 40 through a suitable valve 29 into the container 5, pressure being indicated by the gage 30. The contents of the container are forced out through openings 7, pipe 8 and flexible hose 10 as the container piston is 45 acted upon by the air pressure when the shut off valve 9 is opened. My arrangement of the shut off valve 9 relieves the flexible hose 10 from pressure and eliminates the disagreeable consequences which 50 might follow in case the hose becomes detached from the pipe 8 or should burst.

I prefer to provide a head or cover 6 the full diameter of the container to facilitate its refilling, and this cover, besides being 55 easily opened or closed, must be held securely under all conditions and form an air-

tight joint with the walls of the container. I accomplish this by providing a flange at the top of the container, having a seat for the cover and adjustable bolts for locking 60 the cover on the seat. A rim 11 is mounted on the container walls having an annular seat with a gasket thereon to receive the edge of the disk 6 and bolts 12 are mounted in the rim 11 and levers 13 have forked 65 outer ends to engage the shanks of the bolts and bear on the heads thereof. The disk 6 is provided with an annular rib 16 forming a bearing for the levers 13, their outer ends straddling the shanks of the 70 bolts 12 and engaging the heads thereof, while their inner ends are pivotally connected to a sliding collar 32. A threaded pin 14 is centrally mounted in the disk 6 whereon the collar is slidable and held by 75 means of a wing nut 15. At one side the disk 6 is provided with a hinge 31 on which it tilts when the locking bolts are released by the movement of the wing nut 15. The movement of the nut 15 in one direction 80 will clamp the cover securely on its seat in the top of the container and when the wing nut has been released, the pressure of the levers 13 will be relieved and the cover may then be easily and quickly removed. The 85 dial 17 is graduated for a weight or monetary value, as may be desired, the figures on the dial being visible to the operator as it revolves past the peep opening 28 in the cover.

The indicator is held in place by hangers 19 and a supporting member 18. A sprocket 21 attached to a drum 20 engages suitable holes 34 punched in the dial plate and a cable 22 attached to the piston 24 by a bolt 95 23 causes rotation of the indicating dial as the piston descends, proportionately to the amount of paste or grease dispensed. A spring 33 rewinds the indicating dial when the piston is withdrawn for refilling the 100 container.

I prefer to use a piston in this case having a large opening 26 with an air-tight cover, making it possible to refill the container without removing the entire piston. 105 I also provide a loosely mounted valve 27 which seats on and automatically closes the opening 7 in the bottom of the container as soon as the contents have been discharged, thereby avoiding the escape of air under 110 pressure and its tendency to scatter the oil or grease which may be contained in the

pipe and hose between the container and the nozzle.

The pipe 8 and the hose 10 will normally be filled with grease when the apparatus is in use. That is, the grease will flow from the container into the pipe and hose as soon as air pressure is admitted to the container and when the piston reaches the bottom, air under pressure, if allowed to enter the pipe 10, would force the grease ahead of it until nearly all had been discharged from the hose when the remainder, relieved of the resistance of the grease in front and acted upon by air pressure in the container, would be violently discharged from the hose and scattered over the user as well as the car on which he was working. This would be particularly apt to occur if the user of the apparatus was working under a car and using the hose at that point where he could not see the indicator or determine the position of the piston. In such case the piston might reach the bottom of the container without the operator knowing it and the air flowing around the piston would drive the grease out of the pipe and the hose, with the disagreeable feature above described.

In place of the usual circular piston leather, I prefer to use a straight strip or other suitable packing 35 of proper width for the double flanged piston, as shown, and long enough to reach around the outer circumference of the piston with provision for a suitable splice. The ring or band 36 around the piston flanges provides for proper shape to the facing and secures the same rigidly to the piston.

While I have shown certain preferred details of construction, I do not limit myself

thereto but may make changes therein with- 40 in the scope of the claims without departing from the spirit of my invention.

Having thus described my invention, what I claim and desire to secure by Letters Patent is:

1. In a device of the class described comprising a container with a removable cover, and means for admitting air under pressure, a piston therein, a dial indicator rotatively mounted under said cover, means for connecting said dial indicator with said piston, means for opening and closing said cover, substantially as described.

2. In a device of the class described, comprising a container with a removable head, 55 with means for admitting air under pressure, a discharge valve, a piston therein, means consisting of an indicating dial attached to said cover, or head, said dial operated by a drum and cable, said cable being attached to said piston substantially as described.

3. A device of the class described comprising a container and a removable cover therefor and means for admitting air under 65 pressure, an indicator mounted in said cover, a piston within said container comprising an outer ring section and an inner removable disk section connected with said indicator, said container having a discharge 70 opening and the inner removable section of said piston allowing the filling of said container without removing said outer ring section.

HANS M. BOE.
